CHARLES L. GEORGE, OF FINDLAY, OHIO, ASSIGNOR TO THE BUCKEYE TRACTION DITCHER COMPANY, OF FINDLAY, OHIO, A CORPORATION OF OHIO

BUCKET CHAIN FOR DITCHING MACHINES AND THE LIKE

Application filed August 20, 1928. Serial No. 300,740.

This invention relates to a bucket cleaner adapted to be used in connection with ditching machines and the like, wherein the buckets and the parts associated therewith are arranged in an endless travelling chain to constitute the digging element.

Heretofore, in ditching machines of this type, the digging element has been commonly made up entirely of buckets pivotally connected directly to one another in an endless chain, with each bucket having a rearwardly extending blade or cleaning member secured thereto and adapted to clean the contents from the succeeding bucket as it passes through the upper part of its orbit. Such a construction brings the buckets so close together that the angle between two consecutive buckets does not allow a sufficient sweep for the cleaning element to effect a complete discharge of the bucket.

It has also been proposed to use only half as many buckets and to arrange them alternately with links of the same length, providing each of these links with a blade or cleaning element which projects into the next bucket behind it. Such an arrangement also fails to allow the cleaning element to sweep through a sufficient distance to effect a satisfactory discharge of the bucket.

It is with the object of overcoming the above mentioned difficulties, that the present invention has been perfected. According to the invention, the buckets are connected to each other by intermediate links, but the links are considerably shorter than the buckets, preferably half as long, and each blade projects rearwardly from the preceding bucket, extending longitudinally across the intermediate link into the next bucket, so that the cleaning action begins earlier and continues for a longer time, and the cleaning blade sweeps through a greater angle with respect to the bucket, than is the case when the blade is secured to the intermediate link or when each bucket is connected directly to the next bucket. As a matter of fact, by securing the blade to the preceding bucket, instead of to the intermediate link, the length of the arc, through which the rear end of the blade

sweeps, is increased by a greater ratio than is its angular movement.

My construction, therefore, makes it possible to use a bucket in which the arc at the bottom is of substantial length, and at the same time to swing the cleaning blade far enough to completely discharge the contents of the bucket while the latter is on the upward lap and while the blade is still at a sharp inclination, so that the material will readily slide therefrom.

The specific construction of the invention, together with its mode of operation, will be more fully explained in connection with the accompanying drawing, in which the single figure is a side elevation of the upper portion of a digging element constructed according to the invention.

As shown in the drawing, my invention comprises a series of buckets connected in an endless chain and driven by sprocket gearing 1, which is mounted at the upper end of a boom 2. The buckets 3 alternate with links 4, which are about half the length of the buckets and which are pivotally connected thereto, as indicated at 5. Each bucket has an arcuate bottom 6 with digging teeth 7 suitably secured to the front edge thereof. The buckets also have side walls 8 which are substantially sector shaped and provided with teeth or blades 9 and 10 for cutting the corners. Each bucket has a blade or cleaning element 11 secured to and extending rearwardly therefrom longitudinally across the succeeding link 4 and into the next bucket. As each bucket is filled and starts on its straight upward lap, the blade 11 constitutes a rear wall for the next succeeding bucket, and as the bucket passes over the sprocket gear 1, the blade 11 swings about its pivotal connection 5 to discharge the contents of the bucket onto the usual conveyor arranged to receive the same.

From an inspection of the drawings, it will be noted that each link 4 spans one tooth of the sprocket wheel 1 and each bucket spans three teeth. As each bucket in travelling about the sprocket wheel rocks about its rear pivot 5, assuming that the sprocket wheel has 18 teeth, it will be noted that the bucket swings through an angle of substantially 60° .

before the succeeding link 4 commences to rock. In such a position, the blade 11 has swung far enough to clear the front edge of the bucket while the blade is still at a sharp inclination so that the material will easily slide therefrom. The fact that the blade is secured to the bucket and swings about the pivot at the upper end of the link gives the blade a considerably longer radius, so that its lower end describes a longer arc with the same angular movement, than would be the case if the blade were secured to the link, thus making it possible to use a deeper bucket. It is also to be noted that, by reason of this construction, the cleaning action takes place at an earlier point in the travel of the bucket, in fact, before the link 4 at the upper end of the bucket begins to rock. As the chain continues to travel, the blade 11 continues its turning movement while the succeeding link 4 also turns, while the bucket that is being discharged still continues in its straight path. This results in a still further sweep of the blade in respect to the bucket which is being discharged.

It will be seen, therefore, that with a digging element constructed according to my invention, the cleaning blade is relatively longer, its angular movement is relatively greater with respect to the bucket which it cleans, and the cleaning action begins earlier and continues for a longer time than is the case with digging elements of this type as hitherto constructed. It is also to be noted that the total arc spanned by one bucket and one link together is not an aliquot part of the entire circumference, so that the links and buckets as they pass about the sprocket wheel engage different teeth in each rotation of the wheel so that the wear on the different teeth is equalized.

While I have shown and described specifically one embodiment of the invention, it is to be understood that the various details thereof may be considerably modified without departing from the scope of the invention as claimed.

What I claim is:

1. In a machine of the class described, a chain comprising series of digging buckets and links alternating with each other and pivotally connected end to end, a wheel over which the chain travels, and a blade secured to the rear end of each bucket and extending into the next bucket, normally constituting the back wall thereof but movable to discharge the contents of said next bucket before the latter reaches said wheel.

2. In a machine of the class described, a series of buckets and links alternating with each other and pivotally connected to form an endless chain, a wheel over which the upper part of the chain passes, said chain having a straight upwardly travelling lap adjacent the wheel, and a cleaning member

secured to each bucket and extending rearwardly therefrom into the next bucket, whereby said cleaning member begins its swinging discharging movement while the intermediate link still has some distance to travel on the straight lap. 70

3. In a machine of the class described, a chain comprising series of digging buckets and links alternating with each other and pivotally connected end to end, said chain having an upward travelling straight lap, a wheel at the upper end of said straight lap over which the chain travels, and a blade secured to each bucket and extending rearwardly across the length of the adjacent link into the next bucket, said blade normally constituting a back for the next bucket but movable to discharge material therefrom while the intermediate link is still on the straight lap. 75

4. In a machine of the class described, a chain comprising series of digging buckets and links alternating with each other and pivotally connected end to end, said chain having an upwardly travelling straight lap, a wheel at the upper end of said straight lap over which the chain travels, and a blade secured to each bucket and extending rearwardly across the length of the adjacent link and into the next bucket to the bottom thereof, 80 whereby the extremity of the blade, as the chain passes about said wheel, moves with relation to said next bucket in an arc whose radius is greater than the length of the bucket. 85

5. A digging element comprising series of buckets and links alternating with each other and connected to form an endless chain, and a cleaning member secured to each bucket and extending rearwardly therefrom longitudinally across the adjacent link into the next succeeding bucket. 90

6. A digging element comprising series of buckets and links alternating with each other and pivotally connected end to end, and a blade secured to and projecting rearwardly from each bucket and constituting a back for the next bucket and also a cleaning blade therefor. 110

7. A digging element comprising a series of buckets and links alternating with each other and pivotally connected end to end, a cleaning blade normally projecting into each bucket, and means for rocking said blade about an axis to discharge the contents of the bucket, said axis being in advance of the pivotal connection between the bucket and the link which precedes it. 115

In testimony whereof I have hereunto signed my name to this specification.

CHARLES L. GEORGE.
